EX

DESIGN FOR DOOR-KNOBS.

Specification forming part of Design No. **11,227**, dated June 3, 1879; application filed May 10, 1879.
[Term of patent 7 years.]

UNITED STATES PATENT OFFICE.

RODOLPHE CHRISTESEN, OF HARTFORD, ASSIGNOR TO THE RUSSELL & ERWIN MANUFACTURING COMPANY, OF NEW BRITAIN, CONN.

DESIGN FOR DOOR-KNOBS.

Specification forming part of Design No. **11,227**, dated June 3, 1879; application filed May 10, 1879.
[Term of patent 7 years.]

To all whom it may concern:

Be it known that I, RODOLPHE CHRISTESEN, of the city and county of Hartford, and State of Connecticut, have invented a new and useful Design for Door-Knobs; and I do hereby declare that the following specification, taken in connection with the accompanying photographic illustration, forming a part of the same, is a full, clear, and exact description thereof.

The novel design hereinafter described is adapted to the face of a door-knob, and possesses the characteristic feature of being in the Japanese style of ornament.

As shown in the accompanying illustration, the face of the knob is partially surrounded by an ornamental band, A, which is composed of thin radial bars *a*, in alternation with wider circumferential bars *a'*. A section, B, of com-

ound geometrical ornament, arranged in the form of portions of concentric rings, *b b' b''*, occupies a part of the face of the knob, and extends to its edge. The main portion of the face presents a mottled appearance, and is ornamented by a shrub, C, bearing flowers and leaves, and by a flying bird, D.

The design may be cast in relief or engraved, and is adapted to a knob having a convex, flat, or concave face.

What I claim, and desire to secure by Letters Patent, is—

The Japanese design for the face of a door-knob, substantially as described and shown.

RODOLPHE CHRISTESEN.
